UNITED STATES PATENT OFFICE.

STEVEN L. CARPENTER, OF MOSCOW, TENNESSEE.

BALE-TIE.

SPECIFICATION forming part of Letters Patent No. 329,013, dated October 27, 1885.

Application filed September 14, 1885. Serial No. 177,101. (No model.)

To all whom it may concern:

Be it known that I, STEVEN L. CARPENTER, a citizen of the United States, residing at Moscow, in the county of Fayette and State of Tennessee, have invented a new and useful Improvement in Bale-Ties, of which the following is a specification, reference being had to the accompanying drawings.

My invention has relation to improvements 10 in cotton-bale ties; and the novelty consists in the peculiar construction, combination, arrangement, and adaptation of the various parts for service, substantially as hereinafter fully set forth, and particularly pointed out in the 15 claims.

The object of my invention is to provide a bale-tie which shall be very simple, strong, and durable in construction, quickly and easily applied, not liable to be broken or get out of 20 order, cheap of manufacture, and which can be readily adjusted to tighten the band around the bale.

In the accompanying drawings, Figure 1 is a perspective view of a bale-tie constructed in 25 accordance with my invention. Fig. 2 is a vertical longitudinal sectional view on the line $y-y$ of Fig. 1. Fig. 3 is a bottom plan view showing the band adjusted.

Like letters of reference designate corresponding parts in all the figures of the drawings, referring to which—

A designates my improved tie for hay, cotton, and other bales, and comprising a buckle, B, and a band, C, the two ends C' C² of which 35 are only shown herein.

The buckle B comprises a flat imperforate piece of metal, preferably of steel, for great strength and durability, and having four arms or tongues, b, one arranged at each corner 40 thereof, and bent upon the base-plate to provide hooks c c'.

The hooks c are arranged at one end of the plate, and are bent upon the same to lie on the upper face thereof and parallel therewith 45 to leave an intermediate space, c², between which is fitted the end C' of the bale-band C, while the hooks c' are arranged at the opposite end, and are bent upon the plate in the opposite direction or upon the lower face thereof, and receive the end C² of the bale-band C, which is rigidly secured thereto by fastening 50

or bending or hammering the hooks down upon the base-plate, as is obvious.

Each end C' C² of the bale-band has a cut-away portion, d, at each side thereof, to provide locking-shoulders d' at the sides thereof, which fit over or against the inner bent ends of the hooks of the plate or buckle, said bale-band end fitting snugly against the face of the buckle.

The end C' of the bale-band is provided with two or more of the cut-away portions and shoulders d d', to enable it to be adjusted on the bale to tighten the band and hold the material—cotton, hay, rags, &c.—more firmly together.

To apply my improved bale-band it is only necessary to encompass the bale with the band, to one of which the buckle has been rigidly secured by passing one end of the band (the end C²) between the hooks c' and hammering them down firmly upon the base-piece or buckle, after which the end C' of the band and the buckle B are brought together and the shoulders d' of said end C' locked with the 70 hooks c of the buckle, the intermediate portion of the band between the shoulders thereof fitting in the space between the hooks c, as will be very readily understood.

It will be observed from the foregoing description, taken in connection with the drawings, that my improved bale-band can be rapidly and effectively applied to a bale; that it is simple, strong, and durable in construction, can be manufactured and sold very cheaply, 75 and is not liable to be broken or get out of order.

I attach importance to arranging the hooks on opposite sides of the buckle or base-plate thereof, as thereby I am enabled to facilitate 80 the adjustment of the band in securing it to the buckle after having been passed around the bale, the lower hooks retaining the end C² in position out of the way of the free end of the band.

Having thus fully described my invention, what I claim as new, and desire to secure by Letters Patent, is—

1. A bale-tie comprising a buckle having hooks bent on opposite sides and ends thereof, and a bale-band, one end of which is rigidly connected to one set of hooks and the opposite

end of said band loosely and adjustably fitted between the other set of hooks, substantially as described.

2. As an article of manufacture, a bale-tie comprising a buckle having two integral hooks at opposite ends and bent in opposite directions upon the base-plate, and a bale-band having locking-shoulders d' , one end of the said band being rigidly secured to the hooks on the lower face of the base-plate by bending the said hooks upon the band, and the other end of said

band having its locking-shoulders loosely and adjustably fitted between the hooks on the upper face of the buckle, substantially as described.

In testimony that I claim the foregoing as my own I have hereto affixed my signature in presence of two witnesses.

S. L. CARPENTER.
